CLAIM

The ornamental design for a steel slab reheat furnace skid button, as shown and described.

DESCRIPTION

FIG. 1 is a top perspective view of a steel slab reheat furnace skid button of our new design;

FIG. 2 is a bottom perspective view thereof;

FIG. 3 is a left elevation view thereof;

FIG. 4 is a right elevation view thereof;

FIG. 5 is a front view thereof;

FIG. 6 is a rear view thereof;

FIG. 7 is a top plan view thereof; and,

FIG. 8 is a bottom plan view thereof.

The broken lines show portions of a steel slab reheat furnace skid button that form no part of the claimed design. The zig-zag lines seen in FIGS. 1-4, and FIGS. 7 and 8, are meant to represent a symbolic break in the length of the claimed design, and forms no part thereof. The areas in between the parallel zig-zag lines form no part of the claimed design.
